REFRIGERATING METHOD AND APPARATUS

Walter Jones, Princeton, N. J., assignor to Carrier Corporation, Newark, N. J., a corporation of Delaware

Application December 8, 1936, Serial No. 114,739

14 Claims. (Cl. 62—115)

This invention relates to refrigeration.

It is generally recognized that centrifugal refrigerating systems using low pressure refrigerants, such as carrene (dichloromethane), are 5 highly efficient.

The general object of the present invention is to provide a method of and means for effecting refrigeration in which centrifugal refrigerating apparatus may be used either alone or in conjunction with conventional positive displacement 10 compressing and condensing apparatus to effect refrigeration.

Another object of the invention is to provide a method of and means for augmenting the 15 capacity of existing high pressure refrigerating systems.

Another object of the invention is to provide a method of and means for increasing the capacity of a given refrigerant evaporator, whereby 20 increased refrigerating effect may be obtained economically, as regards both the initial equipment cost and operating cost.

According to the invention, existing refrigerating systems may be provided with auxiliary centrifugal refrigerating systems which become a 25 part thereof and greatly increase the overall refrigerating capacity, without necessitating extensive revision of existing systems and without setting up complete and expensive independent systems.

A feature of the invention resides in supplying refrigerant to an evaporator coil, withdrawing refrigerant from the evaporator coil after it has expanded therein and absorbed heat from the 30 medium surrounding the evaporator coil, passing the withdrawn refrigerant in parallel paths, compressing and condensing refrigerant passed through one of said paths, and condensing refrigerant passed through another of said paths 35 by passing in heat exchange relation therewith other refrigerant having a temperature several degrees lower than the saturation temperature of the withdrawn refrigerant gas, and returning refrigerant condensed in both of said paths to said 40 evaporator coil for reevaporation and recirculation through the system.

Another feature of the invention resides in condensing at relatively low pressure refrigerant gas which is conventionally condensed at relatively 45 high pressure, by circulating in heat exchange relation therewith other refrigerant having a temperature lower than the saturation temperature of the refrigerant gas to be condensed.

Another feature of the invention resides in 50 condensing at relatively low pressure refrigerant

gas which is conventionally condensed at relatively high pressure, by circulating in heat exchange relation therewith other refrigerant, compressing and condensing the other refrigerant at conventionally low pressure, and returning the last-mentioned refrigerant for recirculation in heat exchange relation with other of said first-mentioned refrigerant. 5

Another feature of the invention resides in withdrawing refrigerant gas from the evaporator 10 of a refrigerating system, routing the refrigerant gas in two parallel paths, condensing refrigerant in one of the paths at relatively high temperature and pressure, condensing refrigerant gas in the other of said paths at relatively low temperature and pressure, and returning to the refrigerant evaporator refrigerant condensed in both of said paths. 15

Another feature of the invention resides in evaporating a refrigerant gas, condensing a portion 20 of the gas at high temperature and high pressure, condensing another portion of the gas at low temperature and low pressure, pumping refrigerant liquefied in said last-mentioned step to a different pressure, substantially equal to 25 that at which the high pressure refrigerant is condensed, mixing refrigerant condensed in both of these ways and supplying such mixed refrigerant to the evaporator.

Another feature of the invention resides in 30 withdrawing refrigerant from an evaporator, routing a first portion of the refrigerant in a first path, condensing said first portion of refrigerant at relatively high pressure and temperature, condensing a second portion of said gas at relatively 35 low temperature and pressure, withdrawing air and other non-condensable gases from said second portion of the refrigerant, supplying said withdrawn air to the first portion of refrigerant, and purging the air therefrom. 40

Other objects, features and advantages of the invention will be more apparent from the following description to be read in connection with the accompanying drawing, which diagrammatically represents a refrigerating system in accordance 45 with the invention.

Referring now to the drawing, 5 designates a series of gas suction lines returning from one or more direct expansion evaporators. For purposes of illustration, it will be assumed that ammonia is the refrigerant employed in these evaporators, but it will be understood that the invention contemplates the use of all types of refrigerants whose evaporation and/or condensation is accomplished either at relatively high or low pres- 50

sure. The ammonia gas returning through lines 5 may at times be accompanied by unevaporated liquid and also by oil. Such mixture passes from lines 5 through line 6 into the accumulator 7, 5 where the liquid refrigerant and/or oil falls to the bottom. Thus, nothing but ammonia gas is permitted to pass out of the top of the accumulator 7 through line 8, either through line 9 to the positive compression ammonia compressor 10, or through line 11 to the low pressure condenser generally designated 12. A refrigerant, such as carrene, serving as a condensing medium, is supplied to the condenser 12 through supply line 13 and withdrawn therefrom through return line 14. The temperature of the carrene within the condenser 12 is maintained at a point a few degrees, for example, 8° to 10°, below the saturation temperature of the ammonia gas with which it is passed in heat exchange relation. Thus, 20 the ammonia gas is condensed. Although such apparatus has not been shown, in order to simplify the drawing, it will be understood that associated with the lines 13 and 14 is suitable apparatus for compressing (preferably centrifugal) and condensing the withdrawn carrene gas and for returning it in liquid form to the condenser 12.

Ammonia condensed in condenser 12 passes to receiver 15 through line 16. Pump 17 withdraws ammonia liquid from receiver 15 through line 18 at low or evaporating pressure, and pumps it through line 19 at high pressure to main liquid supply line 20, which feeds the liquid lines 21 connected to the various evaporators of the system. Line 19 is provided with a non-return check valve 22, which permits flow from the pump 17 to the line 20 but prevents flow in a reverse direction.

Ammonia gas compressed by compressor 10 is passed through line 23 to high pressure condenser 24, of any desired type, whence relatively hot ammonia liquid drains to receiver 25 through line 26. It will be noted that main liquid supply line 20 extends into and well below the normal liquid level of receiver 25; it may, if desired, be connected to the bottom of the receiver. Line 20 is provided with a valve 27, lying beyond the junction point of lines 19 and 20, and also with a valve 28 between this junction point and the receiver. Line 19 is provided with a valve 29 between check valve 22 and the junction point of lines 19 and 20.

When condenser 12 is rendered operative, by the circulation of refrigerant supplied thereto through line 13, at the same time that the compressor 10 is operative, valves 27, 28 and 29 are open. Thus, the cold ammonia liquid from condenser 12 can flow out through the lines 21, or can flow down to the high pressure receiver 25.

It is condensing pressure maintained in the condenser 24 which determines the pressure in the liquid feed lines 21 and, consequently, the pressure against which the pump 17 operates. Since valves 27 and 28 are open, no regulation of the capacity of pump 17 is required, since any excess from this pump will go down into the receiver 25. If the pump should be delivering insufficient liquid, the deficiency is made up by liquid which drains down from the high pressure condenser 24. Thus the receiver 25 acts as a balancing tank. When compressor 10 is rendered inoperative and all of the condensation of the system is effected in condenser 12, the valve 28 is closed, while valves 29 and 27 are left open. Under this condition of operation, with a posi-

tive liquid pump, such as 17, means must be provided to vary the pump capacity so as to maintain a constant pressure in the liquid delivery lines 21 under variable flow conditions. This is done by providing pump relief bypass line 30, 5 provided with spring loaded check valve 31, which permits any excess liquid delivered by the pump to be returned to the low pressure receiver 15. Check valve 31 is adapted to open whenever the pressure in line 19 rises above a predetermined 10 point, and hence prevents excessive pressure in line 19.

Obviously, when it is desired to effect condensation in condenser 24 alone, and to render the condenser 12 inoperative, valve 29 is preferably 15 closed while valves 28 and 27 are open. In such case, pump 17, as well as the apparatus associated with refrigerant lines 13 and 14, will be rendered inoperative.

Any air or other non-condensable gases which 20 may get into the ammonia system will gradually accumulate in the low pressure condenser 12 and prevent efficient condensation. Accordingly, a small ammonia compressor 32 is provided, its inlet being connected by line 33 to the last pass 25 of condenser 12, which is the point where air would tend to accumulate. Pump 32 will pump the air and uncondensed ammonia gas through lines 34 to line 23, whence it passes into the high pressure condenser 24. Line 34 is provided with 30 check valve 35 which prevents flow from line 23 to compressor 32. The air delivered to condenser 24, being heavier than the ammonia gas, will finally pass down through line 26 to the receiver 25, whence it may be purged by means of 35 the air purge 36, which may be of any one of many well known types.

Oil is drained from accumulator 7 through drain line 37 provided with a suitable stop cock 38, and refrigerant liquid is drained therefrom 40 through line 39 to line 18 and thus to the intake side of refrigerant liquid pump 17.

To purge the system of air and other non-condensable gases when the condenser 12 alone is operative, (i. e., when compressor 10 and condenser 24 are inoperative) a purge device, generally designated 40, is provided. Within the casing 41 is positioned an ammonia expansion coil 42 which receives liquid refrigerant from the line 19 through the line 43, provided with suitable hand valve 44 and expansion valve 45. Refrigerant expanded in the coil 42 is returned to line 11 through line 46, this refrigerant being recon- 55 densed in condenser 12. Air and other non-condensable gases, and also uncondensed ammonia gas, is withdrawn from the line 34 through the line 47 and supplied to the interior of the casing 41. Preferably, a valve 48 is positioned in line 47 and a valve 49 is positioned in line 34 to control flow through these lines. When the condenser 12 alone is operative, valve 48 is opened and valve 49 is closed; but when the high pressure and low pressure condensers are both operative, the valve 49 is opened and the valve 48 is closed. Gases supplied to the interior of the casing 41 through line 47 contact the cold evap- 65 orating coil 42. Ammonia vapors are condensed and fall to the bottom of casing 41, whence they are returned through line 50 to line 16, leading to the liquid receiver 15. Air and other non-condensable gases are relieved from the casing through line 51, preferably provided with a valve 52 designed to maintain a predetermined pressure within the casing 41.

Thus, it will be apparent that there has been

provided a system in which an auxiliary condensing system may be cut in or cut out, at will, depending upon variations in heat load on the evaporators of the system. When operative, the auxiliary condensing system substantially increases the refrigerating effect produced by the evaporators.

Such an auxiliary condensing system as has been herein described can be quickly and easily installed, and it is to be noted that it in no way impairs the effectiveness or complete utilization of the apparatus in conjunction with which it is used. As a matter of fact, it substantially increases the operating efficiency of such apparatus, since the refrigerant liquid supplied to the evaporators is at a lower temperature, which results in decreased flashing of refrigerant and more useful refrigerating work per unit of refrigerant supplied to the evaporators.

When the invention is used in such installations as breweries, or the like, many of which have long been served by ammonia systems, the centrifugal compressor used to compress the low temperature low pressure refrigerant may frequently be fitted into the heat balance of the brewery, as when the compressor is driven by a steam turbine, utilizing steam which would ordinarily be wasted. Under such conditions, the cost of operating applicant's system and thus providing for increased refrigerating effect is especially low as compared with the cost of operating other types of apparatus.

While the invention has been described with particular reference to the modification of existing ammonia and similar systems, it will be understood that the construction of new systems embodying the invention is deemed within the purview hereof.

Since many changes may be made in the invention without departing from the scope thereof, it is to be understood that the foregoing description and accompanying drawing are intended as illustrative only, applicant limiting himself only as indicated in the appended claims.

I claim:

1. The method of refrigeration which consists in evaporating a refrigerant to absorb heat from a medium to be cooled, condensing a portion of the refrigerant at relatively high pressure, simultaneously condensing another portion of the refrigerant at relatively low pressure, mixing said portions of condensed refrigerant and re-evaporating said mixture.

2. The method of refrigeration which consists in evaporating a volatile refrigerant to absorb heat from a medium to be cooled, compressing one portion of the refrigerant gas, condensing said portion of the refrigerant gas at substantially the pressure to which it has been compressed, simultaneously condensing another portion of the refrigerant gas at relatively low pressure, mixing said portion of refrigerant condensed at high pressure and said pressure of refrigerant condensed at low pressure, and re-evaporating the resultant mixture.

3. The method of refrigeration which consists in evaporating a refrigerant to absorb heat from a medium to be cooled, compressing a portion of the vaporized refrigerant, condensing said portion of the refrigerant at a pressure substantially equal to that to which it is compressed, simultaneously condensing another portion of the refrigerant at a pressure substantially equal to the evaporating pressure, mixing and re-evaporating both portions of the refrigerant.

4. The method of refrigeration which consists in evaporating a refrigerant to absorb heat from a medium to be cooled, routing the resultant refrigerant vapor in parallel paths, compressing the refrigerant vapor passed in one of said paths and condensing said compressed refrigerant at substantially the pressure to which it has been compressed, simultaneously condensing refrigerant passed through another of said paths at a pressure substantially lower than that at which refrigerant in said first mentioned path is condensed, increasing the pressure of said refrigerant condensed at low pressure, mixing said refrigerant condensed at low pressure with said refrigerant condensed at high pressure and re-evaporating the resultant mixture.

5. The method of refrigeration which consists in evaporating a volatile refrigerant to absorb heat from a medium to be cooled, routing the resultant refrigerant vapor in parallel paths, compressing the refrigerant passed in one of said paths and condensing such refrigerant substantially at the pressure to which it has been compressed, simultaneously condensing refrigerant routed in another of said parallel paths at a pressure substantially equal to the evaporating pressure, increasing the pressure of refrigerant condensed in said last-mentioned condensing step substantially to that at which refrigerant is condensed in said first mentioned path, mixing refrigerant from said first path and refrigerant from said other path and re-evaporating the resultant mixture.

6. The method of refrigeration which consists in evaporating a refrigerant to absorb heat from a medium to be cooled, compressing a portion of the resultant refrigerant vapor and condensing said portion at relatively high pressure, simultaneously condensing another portion of the resultant refrigerant vapor at a lower pressure by passing in heat exchange therewith a second refrigerant having a temperature lower than the saturation temperature of the refrigerant vapor to be condensed, mixing the refrigerant condensed at high pressure and the refrigerant condensed at low pressure, and re-evaporating the resultant mixture.

7. The method of refrigeration which consists in evaporating a volatile refrigerant to absorb heat from a medium to be cooled, routing the resultant refrigerant vapor in parallel paths, compressing refrigerant routed in one of said paths and condensing said compressed refrigerant at relatively high pressure, simultaneously condensing refrigerant routed in another of said parallel paths at relatively low pressure, positively withdrawing air and other non-condensable gases from said second path at a point beyond that at which low pressure condensation occurs and increasing the pressure of said withdrawn air and other gases, supplying said withdrawn air and other non-condensable gases to high pressure refrigerant in said first mentioned path, purging said air and other non-condensable gases to the atmosphere, mixing refrigerant condensed in each of said paths and re-evaporating the resultant mixture.

8. A method of refrigeration which consists in evaporating a volatile refrigerant to absorb heat from a medium to be cooled, routing different portions of the resultant vapor in different parallel paths, compressing refrigerant gas routed in one of said paths and condensing said compressed refrigerant at relatively high pressure, simultaneously condensing refrigerant routed in

another of said paths at relatively low pressure, equalizing the pressures obtaining in the downstream portions of said paths, mixing the refrigerant condensed in each of said paths and re-evaporating the resultant mixture.

5. In a refrigerating system, an evaporator, a gas suction line leading from said evaporator, a refrigerant compressor, a first refrigerant condenser, means for supplying gas from said suction line to said compressor, and thence to said first condenser, a refrigerant liquid receiver, a conduit connecting said first condenser with said receiver, a refrigerant liquid supply line leading from said receiver to said evaporator, a second condenser, means for supplying gas from said gas suction line to said second condenser, means for circulating through said second condenser a heat exchange medium for condensing refrigerant gas supplied to said second condenser, means for increasing the pressure of refrigerant condensed in said second condenser to substantially the pressure of refrigerant being discharged from said first condenser, and means connecting the discharge side of said pressure-increasing means and the refrigerant liquid supply line, said pressure-increasing means and said compressor being simultaneously operative.

10. In a refrigerating system, an evaporator, a gas suction line leading from said evaporator, a refrigerant compressor, a first refrigerant condenser, means for supplying gas from said suction line to said compressor and thence to said first condenser, a refrigerant liquid receiver, a conduit connecting said first condenser with said receiver, a refrigerant liquid supply line leading from said receiver to said evaporator, a second condenser, means for supplying gas from said gas suction line to said second condenser, means for circulating through said second condenser a heat exchange medium for condensing refrigerant gas supplied to said second condenser, a liquid pump for increasing the pressure of refrigerant condensed in said second condenser to substantially the pressure of refrigerant being discharged from said first condenser, said liquid pump and said compressor being simultaneously operative, means connecting the discharge side of said pump and the refrigerant liquid supply line, gas pump means whose inlet is connected to the discharge side of said second condenser, means for supplying gas pumped by said gas pump means to said first mentioned condenser, and means in combination with said receiver for purging from the system gas pumped by said gas pump means.

15. In a refrigerating system, an evaporator, a gas suction line leading from said evaporator, a refrigerant compressor, a first refrigerant condenser, means for supplying gas from said suction line to said compressor and thence to said first condenser, a refrigerant liquid receiver, a conduit connecting said first condenser with said receiver, a refrigerant liquid supply line leading from said receiver to said evaporator, a second condenser, means for supplying gas from said gas suction line to said second condenser, means for circulating through said second condenser a heat exchange medium for condensing refrigerant gas supplied to said second condenser, a liquid pump for increasing the pressure of refrigerant condensed in said second condenser to substantially the pressure of refrigerant being discharged from said first condenser, said liquid pump, said liquid pump and said compressor being simultaneously operative.

20. In a refrigerating system, an evaporator, a gas suction line leading from said evaporator, a refrigerant compressor, a first refrigerant condenser, means for supplying gas from said suction line to said compressor and thence to said first condenser, a refrigerant liquid receiver, a conduit connecting said first condenser with said receiver, a refrigerant liquid supply line leading from said receiver to said evaporator, a second refrigerant condenser, means for supplying gas from said accumulator to said compressor and thence to said first condenser, a refrigerant liquid receiver, a conduit connecting said first condenser with said receiver, a refrigerant liquid supply line leading from said receiver to said evaporator, a second refrigerant condenser, means for supplying gas from said accumulator to said second condenser at substantially the pressure prevailing within said accumulator, means for circulating through said second condenser a heat exchange medium for condensing refrigerant gas supplied to said second condenser, means for increasing the pressure of refrigerant condensed in said second condenser to substantially the pressure of refrigerant being discharged from said first condenser, said pressure-increasing means and said compressor being simultaneously operative, and conduit means connecting the discharge side of said pressure-increasing means and the refrigerant liquid supply line.

25. In a refrigerating system, an evaporator, a gas suction line leading from said evaporator, a refrigerant compressor, a first refrigerant condenser, means for supplying gas from said suction line to said compressor and thence to said first condenser, a refrigerant liquid receiver, a conduit connecting said first condenser with said receiver, a refrigerant liquid supply line leading from said receiver to said evaporator, a second condenser, means for supplying gas from said gas suction line to said second condenser, means for circulating through said second condenser a heat exchange medium for condensing refrigerant gas supplied to said second condenser, a liquid pump for increasing the pressure of refrigerant condensed in said second condenser to substantially the pressure of refrigerant being discharged from said first condenser, said liquid pump and said compressor being simultaneously operative, means connecting the discharge side of said pump and the refrigerant liquid supply line, gas pump means whose inlet is connected to the discharge side of said second condenser, means for supplying gas pumped by said gas pump means to said first mentioned condenser, and means in combination with said receiver for purging from the system gas pumped by said gas pump means.

30. In a refrigerating system, an evaporator, an accumulator, a gas suction line leading from said evaporator to said accumulator, a refrigerant compressor, a first refrigerant condenser, means for supplying gas from said accumulator to said compressor and thence to said first condenser, a refrigerant liquid receiver, a conduit connecting said first condenser with said receiver, a refrigerant liquid supply line leading from said receiver to said evaporator, a second refrigerant condenser, means for supplying gas from said accumulator to said second condenser at substantially the pressure prevailing within said accumulator, means for circulating through said second condenser a heat exchange medium for condensing refrigerant gas supplied to said second condenser, means for increasing the pressure of refrigerant condensed in said second condenser to substantially the pressure of refrigerant being discharged from said first condenser, said pressure-increasing means and said compressor being simultaneously operative, and conduit means connecting the discharge side of said pressure-increasing means and the refrigerant liquid supply line.

35. In a refrigerating system, an evaporator, an accumulator, a gas suction line leading from said evaporator to said accumulator, a refrigerant compressor, a first refrigerant condenser, means for supplying gas from said accumulator to said compressor and thence to said first condenser, a refrigerant liquid receiver, a conduit connecting said first condenser with said receiver, a refrigerant liquid supply line leading from said receiver to said evaporator, a second refrigerant condenser, means for supplying gas from said accumulator to said second condenser at substantially the pressure prevailing within said accumulator, means for circulating through said second condenser a heat exchange medium for condensing refrigerant gas supplied to said second condenser, means for increasing the pressure of refrigerant condensed in said second condenser to substantially the pressure of refrigerant being discharged from said first condenser, said pressure-increasing means and said compressor being simultaneously operative, and conduit means connecting the discharge side of said pressure-increasing means and the refrigerant liquid supply line.

40. The method of operating a refrigerating system including an evaporator, a compressor and a condenser, which includes the steps of withdrawing refrigerant vapor from said evaporator, routing a portion of said withdrawn refrigerant in a course bypassing said compressor and condenser, condensing said portion of refrigerant at relatively low pressure while said compressor is operative, increasing the pressure of said portion of refrigerant after condensation thereof, and returning the same to said evaporator for re-evaporation.

45. WALTER JONES. 75
